[57] **ABSTRACT**

Savings bank insertion slot safety mechanism with several locking clasps situated on the inside of the insertion slot and movable against one another and held in a locking position by means of spring tension, the front ends of the locking clasps entering, in the locked position, into the slot up to the middle of the insertion slot and being pressed into released position when a coin is inserted in the slot in which the locking clasps are guided independently of one another and transversely to the insertion slot, the front ends of the locking clasps are tilted downward, and the locking clasps rest with their rear ends each on a common spring element arranged on the corresponding side.

SAVINGS BANK INSERTION SLOT SAFETY MECHANISM

The invention has to do with an insertion slot safety mechanism for a savings bank with several locking clasps situated on the inside of the insertion slot movable against one another and held in a locking position by means of spring tension. The front ends of the locking clasps enter, in the locked position, into the slot and up to the middle of the insertion slot and, when a coin is inserted, the front ends are pressed into one of the positions released by the slot.

In a known insertion slot safety mechanism of this kind (German Patent No. 1,038,805) the locking clasps are housed tiltably against spring tension. These locking clasps in the area of the insertion slot are arranged as tilting edges in the inner or outer vertical sides of tin boxes attached to the wall of the saving bank which accommodate in their hollow spaces the springs which counteract the tipping. The springs are preferably made of rubber springs with rope-shaped hollow profile or full profile, whereby the locking clasps are supported either directly to the springs or else through a squared-off side. These tin boxes on both sides of the insertion slot, which serve as tilting edges and which accommodate the springs, have a relatively great overall height. Consequently, the inside space of the savings bank is reduced in size.

In another known form of the kind described above (German Patent No. 357,532) the locking clasps are held securely to both sides of the insertion slot so that by means of spring clasps of a plate which is composed of spring sheet metal and attached to the underside of the cover with its front sides turned away from the insertion slot, they are pressed against a stop, whereby the locking clasps with pick-shaped ends engage into the notches of the locking clasps in the vicinity of the stop.

In other known forms of insertion slot safety mechanisms (U.S. Pat. No. 1,115,606 and French Pat. No. 706,981) the locking clasps are supported by fixed axles and weighted by means of springs so that they always return to the locked position.

These known insertion slot safety mechanisms for savings banks have the basic drawback that they require a relatively large, free space because of the rotatable arrangement of the locking clasps.

The invention, therefore, has the object of designing an insertion slot safety mechanism of the kind described above in such a way that it is possible to obtain a reduction in space with simple construction.

This object is achieved in the case of a savings bank safety mechanism of the kind described above, according to the invention, in that the locking clasps which are guided adjustably independently of one another and transversely to the insertion slot, the front ends of the locking clasps are tilted downward, can rest with their rear ends each on a common spring element situated on the corresponding side. Since the individual locking clasps are guided adjustably vertically to the slot in the wall of the savings bank which accommodates the insertion slot the necessary space occupied corresponds to the thickness of these locking clasps plus an appropriate guide which can also be made very flat. Since the front ends of the locking clasps are tilted downward when a coin is inserted there occurs a force component

acting in the longitudinal direction of the locking clasps, and they are moved out of the insertion slot against the force of the spring element. In order to make it still more difficult for the coins to slip out in the opposite direction, the edges which are turned away from one another of the ends which are tilted downward of the locking clasps can be beveled.

In order to achieve the most simple possible holding of the spring element and a simple guiding of the locking clasps, according to a further development of the invention, there is a plate on both sides of the insertion slot. This plate lies on the wall of the savings bank and it has recesses opened to the wall of the savings bank. In these recesses the spring element is held and the locking clasps are guided. By means of this plate, which is only slightly thicker than the locking clasps, it is possible to obtain a holding support and guide for the spring elements and the locking clasps which is simple in design and requires little space.

According to a further development of this invention, it is possible to provide on the adjustable locking clasps shift path limiting stops which are opposite counterstops on the clasp guides. Thus, according to a preferred embodiment, extensions are directed mutually to both sides of a guide for the locking clasps. These extensions engage in a side recess of the locking clasps, whereby the recesses in the longitudinal direction of the locking clasps exceed the dimensions of the extensions by the necessary displacement path.

According to a further development of the invention, the spring element is a spring cushion made of elastic material such as elastic, foamy material. The spring cushion in this case can be beam-shaped and the rear ends are supported with very flat front surfaces to a side face of the beam-shaped spring cushion. The utilization of a spring cushion made of elastic material has the advantage that it is possible to obtain a completely independent support of the individual locking clasps without any mutual interference.

Naturally, instead of a spring cushion we could use a corrugated steel spring which also permits a nearly independent spring suspension of the locking clasps.

Preferably, the locking clasps and/or the guides are made of a material with a low coefficient of friction in order to permit an easy sliding of the locking clasps in the guides.

The invention is represented by way of example in the drawings.

FIG. 1 is a top view of a savings bank insertion slot safety mechanism made as a built-in unit;

FIG. 2 shows this insertion slot safety mechanism without a cover plate;

FIGS. 3 and 4 show a cross-sectional view through the insertion slot safety mechanism; and

FIG. 5 shows an assembly view of the parts forming the insertion slot safety mechanism.

The insertion slot safety mechanism for savings banks which is represented in the drawings is designed in the form of a block as a built-in unit which can be inserted in a correspondingly cut out cover of a savings bank.

The overall built-in unit is composed of a cover plate 1 and a base plate 2 which is provided with recesses 3 and 4.

Slots 5 and 6 are provided both in the cover plate 1 and in the base plate 2. In the assembled state these slots are superimposed over the built-in unit and serve as an insertion slot for coins 7.

Locking clasps 8 are provided in the recesses 3 transversely to the insertion slot 5 and 6. These locking clasps reach with their front ends 9, which are tilted downward, in their locked position up to the middle of the insertion slot. The rear ends with their stumps cut off the locking clasps 8 rest against a spring cushion 10 in the shape of a beam which is made of elastic, foamy material. The spring cushions 10 are held in the recesses 4 of the base plate 2. In the embodiment which is illustrated, the recesses 4' corresponding to the recesses 4 are provided with small depth in the cover plate so that still a part of the spring cushion 10 engages into the recesses 4', as can be seen from FIGS. 3 and 4. When a coin 7 is inserted, the locking clasps are pushed away from one another because of the spring force of the spring cushion 10, which thereby becomes deformed, as is shown in FIG. 4. Instead of the spring cushion 10 we can also use a corrugated steel spring 11 which is inserted into the recess 4 (FIG. 2) so that the corrugated spring can stretch with the return of the locking clasps 8.

The clasps 8 have on both sides recesses 12 into which extensions 13 engage on both sides of the recesses 3 serving for longitudinal direction, whereby the length of the recesses 12 is greater by the amount of the necessary shift path than the size of the extension 13 extending in the longitudinal direction of the locking clasps. As can be seen from FIG. 2, the locking clasps 8 slide between elongated ridges 14 on cover plate 1 and base plate 2.

In the embodiment which is shown, the cover plate 1 and the base plate 2 are composed of a ductile elastic synthetic material. Recesses 15 are provided on the edges of the base plate 2 at various points. Hook-shaped extensions 16 of the cover plate 1 engage into these recesses, as a result of which both plates are connected to one another. Mutually aligned eyelets 17 are provided on two opposite sides of the cover plate 1 and the base plate 2. These eyelets 17 serve the purpose of securing the built-in unit in a recess of a savings bank. Of course, the base plate 2 can be secured with the inserted locking clasps 8 and spring cushions 10 directly onto the wall of a savings bank which (the wall) is provided with an insertion slot, for example, by screwing in

which case a separate cover plate is not necessary.

What is claimed is:

1. A safety mechanism for a savings bank including a cover surface provided with an insertion slot, comprising a plurality of pairs of blocking tongues located adjacent to the insertion slot and mounted for transverse movement relative to the insertion slot, the front ends of the blocking tongues abutting in the middle of the insertion slot in closed positions, and the blocking tongues being forced back into positions allowing access through the slot when a coin is inserted, a base plate having a central slot in registration with the insertion slot and a plurality of guides for receiving and guiding the blocking tongues in transverse movement relative to the insertion slot and parallel to the cover surface of the savings bank, and a common spring element located on each side of the insertion slot for engaging the blocking tongues on that side to urge the blocking tongues into the closed positions.
2. A safety mechanism for a savings bank insertion slot according to claim 1, wherein the blocking tongues are provided with limit stops and the guides of said base plate include counter stops cooperating with the limit stops for limiting movement of said tongues relative to said guides.
3. A safety mechanism for a savings bank insertion slot according to claim 1, wherein oppositely located stops are provided on both sides of the guides for the blocking tongues, the stops engaging lateral recesses formed in the blocking tongues, and the lateral recesses having clearances longitudinally along the blocking tongues exceeding the size of the counter stops by the required length of displacement.
4. A safety mechanism for a savings bank insertion slot according to claim 1, wherein the spring element consists of an elastic padding such as elastic foam.
5. A safety mechanism for a savings bank insertion slot according to claim 4, wherein the elastic padding is beam-like and the rear ends of the blocking tongues include flat surfaces for engaging a lateral surface of the beam-like elastic padding.
6. A safety mechanism for a savings bank insertion slot according to claim 1, wherein the spring element consists of an undulatory steel spring.
7. A safety mechanism for a savings bank insertion slot according to claim 1, which includes a cover plate mounted over said base plate to confine said blocking tongues in said guides.
